SEA WALL AND METHOD OF MAKING SAME.

Application filed November 30, 1925. Serial No 72,311.

Sea walls, or retaining walls, or bulkheads along water fronts, especially salt water fronts, have to contend with conditions of outward pressure from the land side, the force and lapping effect of the water on the water side, and the destructive effect of marine borers, and of the corrosive or oxidizing effect of salt water on metal. These conditions call for strength, rigidly or stability, and safeguarding from the work of marine borers and corrosion by the action of salt water. The primary object of our invention is to provide a bulkhead, or seal wall construction, which will successfully deal with the conditions just briefly mentioned, and above all will do that at the minimum of cost of construction, which, of course, is a highly important consideration.

Our invention consists in whatever is described by or is included within the terms or scope of the appended claims.

In the accompanying drawings which are illustrative of our invention, but not restrictive of the scope thereof:

Fig. 1 is a front elevation showing the structure in process of erection;

Fig. 2 is a detail view of a portion of the upper part of the structure shown in Fig. 1;

Fig. 3 is a top plan view of what is shown in Fig. 2;

Fig. 4 is a view in vertical section of the completed structure, the forms used in casting the concrete having been removed and the vertical precast slab being shown as united with the horizontal slab which is poured after the placing of the vertical slab.

Fig. 5 is a horizontal section on the line 5—5 of Fig. 4, which shows the structure during construction, and with the inclined piling, 13, not shown in section.

Fig. 6 is a vertical section showing the application of our invention to existing timber bulkheads.

Figs. 7 and 8 are similar views of other applications of our invention to existing timber bulkheads.

Referring to what is shown in the drawings, in the practice of our invention as we now consider that to be most advantageously done, we drive or employ two parallel rows of timber piles, a front or outer row, 10, and a back or inner row, 11, spaced apart, front to back, say two feet, six inches, on centers (although, of course, we do not restrict ourselves to this spacing), and the piles of each

row being spaced apart at desired intervals longitudinally or in the direction of the length of the row. The tops of these piles are cut off at proper elevations and the piles will be stayed back or jacked out to line, as may be necessary. At their upper ends the alining piles of the front and back rows are tied together by a bolt, 12, which extends at an incline or slope downwardly or rearwardly, this bolt connection giving stiffness and stability that will resist effectually any rocking or turning motion of the structure due to outward pressure of the earth fill. If desired, a batter timber pile, 13, bolted to the upper end of the pile of the inner row of piles may be employed, that extends downwardly and forwardly, as clearly shown in Fig. 4, such a batter pile being desirable under some conditions for anchorage to resist outward pressure by the earth fill.

To the outer side of the piles of the outer row is applied a precast slab of reinforced concrete, the slab being made in sections of suitable length having reference to the longitudinal spacing of the piles, the vertical joints between adjacent sides being preferably located in line with the vertical center of the piles, and the slab sections being of dimensions vertically that will result in the embedding of the lower portions thereof into the sea bottom, say for illustration from six inches to twelve inches. The slab sections are reinforced vertically and also horizontally as well, preferably, by suitable reinforcement which, preferably, consists in spaced apart vertical rods, 14, and spaced apart horizontal rods, 15, the vertical rods extending, preferably, above the top of the slab sections for a purpose presently to appear. The slab sections have embedded in them at the upper part, rods that are bent to form eyes or loops, 16, projecting above the top by which the slabs are suspended from the piles, as by means of hooks, 17, secured to the tops of the piles, and, preferably, by the arrangement shown in Fig. 3, where the hooks extend divergently to the tops of adjacent slab sections, and thus, serve to hold the abutting side edges or joints together. Of course, other suspending means may be employed and different forms of suspending means may be employed if the piles are driven off center. The matter of the joint between the slab sections is of vital importance, because it must be so tight as to preclude the entrance of sea

water which would result in the disintegration of the slab. We, therefore, make a dovetail connection at the abutting edges, or a tongue and groove connection, the tongue, 18, being preferably wedge-shaped and the groove correspondingly inclined.

The slab sections having projecting from their sides next to the piles, rods, 19, of sufficient length to straddle the pile and project to the rear thereof, and the projecting ends of these rods are twisted so as thereby to secure or anchor the slab sections to the front piles, as a temporary support.

With the process of erection carried as has thus far been described, the next step is the casting of concrete around each of the front piles, to surround each pile with concrete and to fill the space between the inner side of the slab sections and the pile, and thus, unite the slab sections and the concrete poured around the pile, and thus, safeguard the enclosed pile from access of sea water. For this step of the operation a form or box, 20, is built of sheet piling around each pile, as shown in Fig. 5, and into the form thus provided, the concrete is poured and in dealing with sea water preferably tremie concrete is used.

After allowing time for hardening of the tremie concrete, say twenty-four hours, the space behind the slab sections is filled to a level below the tops of the piles of the two rows, and then forms are set flush with the face of the slab and to a suitable distance behind the rear piles. Reinforcement consisting preferably of rods, 21, is placed and then concrete is poured to cover the space above the top of the fill, and above the upper ends of the piles, and to embed the upwardly projecting portion of the vertical rods of the slab sections, and thus, a horizontal slab, 22, of reinforced concrete is provided, having at the front an upwardly extending flange or curb, 23, giving to the horizontal slab thus formed an L-shape. The curb supports the fill to the grade above the horizontal portion of the slab, 22. It will be seen that by means of the vertical reinforcing rods of the slab sections and the embedment thereof at their upper ends in the horizontal slab, 22, the precast slab sections derive their vertical support by these rods, and hence, even though by scouring action of the water, the earth or sea bottom support at the bottom of the slab should be removed, the vertical face slab will nevertheless be supported in position and thus the integrity of the structure preserved. Obviously should the vertical face slab depend for its support upon the sea bottom, if the latter should be washed away, the slab structure would collapse.

It will be seen that although timber piling is used, and iron rods or bolts are used, both metal and wood are protected from the action of the destructive forces all around them,

whether the action of the water itself or marine borers. The front piles are protected by the complete encasement of concrete. Danger of rotting of the rear piles is prevented by placing the horizontal top slab, 22, at such a level, that the fill below it is at all times saturated by capillary attraction to a point at least two feet above mean tide levels, and thus, the piles are kept in a continually saturated state.

Our sea wall has all the stability and durability of the usual form of an entirely concrete bulkhead, yet because of its employment of timber piling, the cost of construction is much less than that of an all concrete construction. All the work of installation is done above the water line, and hence, economy of construction is secured compared with types of construction which require the use of cofferdam work and pumping. Although we use tremie concrete, yet the quantity required is so small that it may be economically mixed by hand.

As illustrated in Fig. 6, our invention is shown applied in connection with timber bulkheads already erected, the original bulkhead construction comprising only the rear row of timber pilings.

In Figs. 7 and 8 which show other arrangements for utilizing our invention with timber bulkheads already erected, a slab at the top corresponding with the horizontal slab, 21, of Fig. 4 is omitted and in each case the precast slab is poured or formed with a coping at the top which on its inner side has an inwardly projecting flange. This flange, 24, in the case of Fig. 7 rests upon the top of the front piling, 100, and is thereby supported in addition to the support derived from the rods, 190, embedded in the concrete encasing the piles, 100. In Fig. 8 the original piling, 111, is utilized as the front or supporting piling for the precast slab, and the coping flange, 25, may rest upon the tops of such original pilings, or if the original piling has been partially destroyed by marine borers, or has deteriorated from other causes, the upper part may be cut off and the concrete cast about the cut off pilings is carried above the same to the desired level, and upon the top thereof, said coping flange, 25, rests. In the case of the construction shown in Fig. 8, ties, 26, extend back to the original anchor pile.

What is claimed is:

1. A sea wall comprising spaced rows of wood piling, one row being nearer the water than the other, a concrete slab between the front row and the water, a fill in rear of said slab, and a horizontal slab at the tops of the rows of piling and joining with the top of the slab situated between the front piling and the water.

2. A sea wall comprising spaced rows of wood piling, one row being nearer the water than the other, a concrete slab between the

front row and the water, a fill in rear of said slab, and a horizontal slab at the tops of the rows of piling and joining with the top of the slab situated between the front piling and the water, said horizontal slab having an upwardly extending curb next to the water.

3. A sea wall comprising spaced rows of wood piling, one row being nearer the water than the other, a concrete slab between the front row and the water, a fill in rear of said slab, a horizontal slab at the tops of the rows of piling and joining with the top of the slab situated between the front piling and the water, and concrete surrounding the pilings of the front row and reaching to the slab between said pilings and the water.

4. A sea wall comprising spaced rows of wood piling, one row being nearer the water than the other, a concrete slab between the front row and the water, a fill in rear of said slab, a horizontal slab at the tops of the rows of piling and joining with the top of the slab situated between the front piling and the water, said horizontal slab having an upwardly extending curb next to the water, and concrete enclosing the portions of the piles of the front row adjacent the slab lying over such piles.

5. A sea wall comprising wood piling, a concrete slab extending between such piling and the water, means independent of the sea bottom supporting such slab, including means suspending the slab at the top from the tops of the adjacent pilings.

6. The method of constructing sea walls which consists in providing rows of pilings, one row being back of the other row, supporting a precast concrete slab between the front row of pilings and the water, applying concrete protecting means to the pilings of the front row and joining the same to the precast slab and finally pouring a horizontal slab of concrete at the tops of the pilings and the top of said slab and joining the same to the top of said precast slab.

7. The method of constructing sea walls which consists in providing rows of pilings, one row being back of the other row, supporting a precast concrete slab between the

front row of pilings and the water, applying concrete protecting means to the pilings of the front row and joining the same to the precast slab, making a fill in rear of the precast slab, and finally pouring a horizontal slab of concrete at the tops of the pilings and the top of said slab and joining the same to the top of said precast slab.

8. A seawall comprising a piling, a precast concrete slab extending vertically between the piling and the water, rods projecting rearward from said slab, a body of concrete extending over the top of the piling, and joining with said slab, and concrete extending around the piling, and reaching to and united with the inner side of said vertical slab and embedding said rods which project rearward from the slab.

9. The method of constructing sea walls which consists in supporting a precast concrete slab between the piling and the water, applying concrete protecting means about the piling where the piling is not covered by such slab, and joining the same to the precast slab, and finally forming a horizontal slab of concrete at the top of said precast slab and the top of said piling.

10. A seawall comprising piling arranged in two rows, one back of the other, a precast slab supported between the piling next to the water and the water, a fill in rear of such precast slab supported against outward pressure by the slab, concrete around the piling at the inner side of the precast slab and joined to the latter, and a body of concrete extending over the tops of both rows of piling and united with the inner side of said vertical slab.

11. A seawall comprising piles, a vertical concrete slab between the piles and the water, rods embedded in and projecting rearward from said slab and concrete about said piles into which the rearwardly projecting portions of said rods enter.

In testimony whereof we hereunto affix our signatures.

ROBERT M. MILLER. [L. s.]
HERBERT D. HODGSON. [L. s.]
